(57) **CLAIM**

The ornamental design for a female connector with contact pads, as shown and described.

DESCRIPTION

FIG. 1 is a front, top and left side perspective view of a female connector with contact pads showing our new design.

FIG. 2 is a top plan view thereof.

FIG. 3 is a front side elevational view thereof, the undisclosed rear side elevational view being identical thereto;

FIG. 4 is a bottom plan view thereof; and,

FIG. 5 is a left side elevational view thereof, the undisclosed right side elevational view being identical thereto.

The broken lines of FIG. 4 are included to show environmental structure and form no part of the claimed design.
